[57] CLAIM

The ornamental design for a video cassette storage tray, substantially as shown and described.

DESCRIPTION

FIG. 1 is a perspective view of a video cassette storage tray showing our new design;

FIG. 2 is a left side elevational view thereof, the right side being a mirror image of FIG. 2;

FIG. 3 is a vertical cross-sectional view taken between one of the slots in FIG. 4;

FIG. 4 is a front elevational view thereof;

FIG. 5 is a top plan view thereof;

FIG. 6 is a rear elevational view thereof; and

FIG. 7 is a bottom plan view thereof.
